UNITED STATES PATENT OFFICE.

JOHN MARSHALL PARKINSON, OF TORONTO, CANADA, ASSIGNOR TO
AMBROSE KENT & SONS, OF SAME PLACE.

DETACHABLE FASTENER FOR CUFF-LINKS.

SPECIFICATION forming part of Letters Patent No. 599,353, dated February 22, 1898.

Application filed October 8, 1896. Serial No. 608,255. (No model.)

To all whom it may concern:

Be it known that I, JOHN MARSHALL PARKINSON, jeweler, of the city of Toronto, in the county of York, in the Province of Ontario, Canada, have invented certain new and useful Improvements in Detachable Fasteners for Cuff-Links and Similar Articles, of which the following is a specification.

My invention relates to improvements in adjustable fasteners for cuff-links and similar articles; and the object of the invention is to design such a fastener as when once secured will be impossible to become detached of itself; and it consists, essentially, in making the fastener in two parts, one part being tubular in form and fastened to one part of the cuff-link or like article and having the outer end with a notch formed in the edge thereof and the other part being in the form 15 of a stem, which is secured to such part of the cuff-link or like article, the said stem having an inner enlargement and a projection made on such enlargement, which is of corresponding cross-sectional shape to the notch 20 in the tubular portion, the said parts being arranged to fasten together in the manner hereinafter more particularly explained.

Figure 1 is a perspective view of a cuff-link connected together in accordance with my invention. Fig. 2 is a similar view showing the link separated. Fig. 3 is an enlarged detail of the button, showing the construction of the stem portion attached thereto. Fig. 4 is an enlarged detail, partially in section, showing the other portion of the button with the tubular portion connected thereto. Fig. 5 is 25 a cross-section of a collar-button.

In the drawings like letters of reference indicate corresponding parts in each figure. 30 In Figs. 1, 2, 3, and 4, A is one ornamental end of the link, and C the other. In the center of the back of the end A is secured a stem B by the inner flange b, such stem being secured to the back by solder or in any other 35 suitable manner.

b' is the enlarged portion of the stem, and b² is the reduced portion.

b³ is a projection formed on the enlarged portion b' and at the outer end thereof.

40 C' is a tubular stem which has an inner

flange c, by which it is attached to the ornamental end C.

C² is a tubular stem which is soldered to the outside of the tubular stem C, as indicated. The outer end of the portion C² has 45 an inwardly-extending flange c², provided with a notch c³, thus leaving a hole c⁴, corresponding substantially in diameter to the enlargement b' of the stem B and having the notch c³, corresponding to the cross-sectional 50 size of the projection b³.

D is a spiral spring located within the tubular stem C'.

Although I show the tubular stem made in 55 two portions C' and C², it will of course be understood that it might be readily made in one portion; but I prefer making it in two when the ornamental ends are made of gold; but in cheaper classes of goods it would merely be made in one portion.

In order to fasten the parts together, the 60 stem B is inserted in the tubular stem C², the projection b³ being brought opposite to the notch C³, so that it may pass readily into the tubular stem C², the end of the enlargement 65 b' pressing against and pushing back the spiral spring D. When the inner end of the enlargement b³ has passed the end of the notch c³, the end A may be turned around quickly, 70 so as to bring the inner end of the projection b³ against the flange c². The spiral spring D will now serve to securely hold the inner end 75 of the projection b³ against the flange c² of the tubular stem C², thereby serving to securely fasten the parts together in their proper position.

In Fig. 5 I show the alternative form used 80 for a collar-button or stud, in which I provide the top E with the solid stem and the base F with a tubular stem. The parts, however, are exactly identical in form and operation. Many like articles of jewelry in common use may also be provided with the same fastening.

It will be seen that where my fastener is 85 used for sleeve links and buttons or studs all danger of crushing the linen is entirely obviated, as the stem may be readily inserted through the holes.

What I claim as my invention is—

A fastener for cuff-links, and the like, comprising one disk-shaped end having an im-
5 perforate sleeve extending therefrom with an annular flange projecting inwardly at the end
thereof to form a contracted opening, and a recess in the flange extending from the edge
of the opening to the inner wall of the sleeve, a spiral spring within the sleeve permanently
10 confined between the flange and the disk-
shaped end, and a second disk-shaped end
having a stem extending therefrom adapted
to closely fit into the reduced opening in the
sleeve, a projection extending from the side
15 of said stem adapted to pass through the re-
cess in the flange and to be pressed against
the under side of said flange by said spring

when the stem is inserted within the sleeve
and turned, and a reduced extension project-
ing centrally from the end of the stem adapt-
ed to first enter the reduced opening to guide 20
the larger portion of the stem therethrough,
said extension passing within the coils of the
spring whereby the stem will be prevented
from wobbling by the close fit of the flange
about the larger part thereof and by the spring 25
surrounding the extension, substantially as
described.

JOHN MARSHALL PARKINSON.
